UNITED STATES PATENT OFFICE.

CHARLES A. REINERS, OF CHICAGO, ILLINOIS, ASSIGNOR OF ONE-HALF TO ELEVATOR SUPPLY & REPAIR COMPANY, OF CHICAGO, ILLINOIS, A CORPORATION.

SIGNALING APPARATUS FOR ELEVATOR-CARS.

SPECIFICATION forming part of Letters Patent No. 733,750, dated July 14, 1903.

Application filed April 17, 1899. Serial No. 713,227. (No model.)

To all whom it may concern:

Be it known that I, CHARLES A. REINERS, a resident of Chicago, in the county of Cook and State of Illinois, have invented certain new and useful Improvements in Signaling Apparatus for Elevator-Cars, of which the following is hereby declared to be a full, clear, and exact description.

This invention relates more particularly to that class of signaling apparatus for elevator-cars in which an electric signal (usually an incandescent lamp within the elevator-car) is controlled by the operation of push-buttons or like circuit-controlling mechanism upon the several floors of the building through which the elevator-car passes.

The invention consists in the various features of improvement hereinafter described, illustrated in the accompanying drawings, and particularly defined in the claims at the end of this specification.

Figure 1 is a diagrammatic view showing part of an elevator-hatchway with a car therein and showing my improved means whereby the signal within the car is controlled. Fig. 2 is an enlarged detail view, in side elevation, of the magnets and mercury-pots whereby the passage of current to the controlling-magnets within the hatchway of the elevator is determined. Fig. 3 is a plan view of the part shown in Fig. 2. Fig. 4 is a face view, and Fig. 5 a view in central vertical section, through a form of circuit-controllers that are placed in the hatchway and on the car. Fig. 6 is a plan view, and Fig. 7 is a view in section, through a form of magnet that is used in both the hatchway and in the car. Fig. 8 is a side view, and Fig. 9 is a face view, of a form of circuit-controller that is used in the circuit wherein the floor-lanterns are placed. Fig. 10 is a diagrammatic view showing an elevator-hatchway and car, illustrating the means for automatically operating the switch within the car. Fig. 11 is an end view, and Fig. 12 a plan view, of the automatic switch within the car. Fig. 13 is a diagrammatic view showing the invention as provided with means for controlling the lighting of lanterns upon the floors of the building.

In the diagrammatic view Fig. 1 of the drawings I have shown the mechanism appertaining to a single floor of the building, since it will be understood that corresponding mechanism will be used upon all the floors. A designates the hatchway through which will pass the elevator-car A', it being understood, of course, that this car will be furnished with any suitable mechanism for operating the same and will be furnished with a suitable cable whereby the electric wires a and a' will be led to the car from a rotary transformer or other source of current. At a convenient point, preferably adjacent each of the floors of the building, is placed the mechanism illustrated diagrammatically at the left-hand side of Fig. 1 of the drawings. This mechanism is shown as comprising two pairs of magnets, one pair serving to control the signaling of the car by an intending passenger desiring to ascend and the other pair serving to control the signaling of the car by an intending passenger desiring "down" service. The magnets b and c of the "up" signal controlling mechanism, and which are hereinafter termed the "releasing" and "restoring" magnets, are mounted upon a frame B, that is carried by an insulating-block C. At one side of the magnet b extends an arm b', to the end of which is pivoted an armature-lever b², (see Fig. 2,) the bent end of this lever being, preferably, furnished with a set-screw b³ to limit the throw of the lever. At one side of the magnet c extends the upper arm c' of the frame B, to which is pivotally connected an armature-lever c², that normally extends beneath and is held by the armature-lever b² of the releasing-magnet b. The outer end of the armature-lever c² is preferably furnished with a set-screw that engages a stop to limit its downward movement, and the extreme end of this armature-lever has connected therewith a rod or wire c³, adapted to dip into the mercury-pot D when the rear end of the armature-lever c² is released from engagement with the end of the armature-lever b². The frame B' of the "down" signal controlling mechanism carries two magnets b⁶ and c⁶, corresponding with the magnets b and c

above described, the magnet b^6 having an armature-lever b^7 pivoted adjacent thereto, while the magnet c^6 has an armature-lever c^7 , that carries at its outer end a rod c^8 , adapted to dip into the mercury-pot D' . At a convenient point adjacent the elevator-hatchway are placed two push-buttons E and E' , the push-button E serving for "up" signaling service and the push-button E' serving for "down" signaling service. These push-buttons are of any ordinary or suitable type, being normally open. One contact-point of the push-button E is connected by a branch e with a wire 2, that leads to the main feed-wire 3, to which current is delivered from a source of supply connected at its end X . A branch e' from the wire 2 connects one terminal of the "down" push-button E' with the main feed-wire 3. From the opposite contact-point of the "up" push-button E a wire e^2 leads to the magnet b of the "up" signal controlling mechanism, and from the corresponding contact-point of the "down" push-button E' a wire e^3 leads to the magnet b^6 of the "down" signal controlling mechanism. It will be seen that the signal-controlling mechanism connected with the "up" push-button and that connected with the "down" push-button are identical. From the magnet b of the "up" signal controlling mechanism, for example, a wire f leads to a wire f' , that connects with a branch wire 4, that leads to the main feed return-wire 5, the free end Y of which wire will be connected with a rotary transformer or other suitable source of supply at a convenient point. A branch f^2 from the wire f' leads to the magnet c , and from this magnet c a wire g leads to a circuit-controller G , located in the hatchway opposite the floor corresponding to the circuit-controlling mechanism with which it is connected. From the circuit-controller G a wire g' leads to the main feed-wire 3. The wire g' is connected by a wire g^2 to a signal-circuit controller G' , that is connected by a wire g^3 with the magnet c^6 of the "down" signal controlling mechanism, and it will be seen that the magnets b^6 and c^6 of the "down" signal controlling mechanism are connected by branch wires f^4 and f^5 , that are connected by a branch wire f^6 to the wire 4, that unites with the return-wire 5. From the mercury-pot D leads a wire d^2 to a controlling-magnet H , that is located in the hatchway about or at slight distance below the level of the floor of the corresponding signal-controlling mechanism, and this controlling-magnet H is connected by a wire d^3 with a signal-controlling magnet H' , that is connected by a wire d^4 with the return-wire 5. From the mercury-pot D' of the "down" signal-controlling mechanism leads a wire d^5 to a controlling-magnet H^2 , that is connected by a wire d^6 with a similar controlling-magnet H^3 , from which magnet a wire d^7 leads to the main return feed-wire 5. From the branch wire 2, that connects with the main feed-wire 3, a branch wire b^5 leads to the frame B of the "up" signal control-

ling mechanism, and from the branch wire 2 a branch wire b^9 leads to the frame B' of the "down" signal controlling mechanism.

From the foregoing description it will be seen that when an intending passenger desiring to go upward presses the push-button E the circuit will be closed at such point. Current will then pass from the source of supply by main feed-wire 3 and branch wire 2 and wire e to push-button E , thence by wire e^2 to magnet b . From magnet b current will pass by wires f^2 and 4 to feed-wire 5 and back to source of supply. The magnet b being thus energized will attract the armature b^2 and withdraw it from engagement with the rear end of armature c^2 , thereby permitting the wire c^3 at the outer end of the armature c^2 to drop into mercury-pot D and close the circuit at such point. Current will then pass from main feed-wire 3 by wire 2, by wire b^5 to frame B , to armature-lever c^2 , to wire c^3 , to mercury-pot D , and thence by wire d^2 through controlling-magnet H , by wire d^3 through controlling-magnet H' , and by wire d^4 to main feed-wire 5, and thence back to source of supply. The controlling-magnets H and H' will thus be energized and will so remain until they have performed the function of operating the signal within the car in manner to be presently described and until the restoring mechanism to be presently described serves to return the signal-controlling mechanism at the floor to its normal condition. In like manner it will be seen that if an intending passenger operates the push-button E' the circuit at such point will be closed and current will pass from main feed-wire 3 by wires 2 and e' to the push-button E' , thence by wire e^3 to magnet b^6 of the "down" signal controlling mechanism, thence by wires f^4 and f^6 and 4 to the main return feed-wire 5, and by this wire back to the source of supply. The effect of this passage of current through the magnet b^6 will be to attract its armature-lever b^7 , thereby releasing the armature-lever c^7 and permitting its wire c^8 to drop into the mercury-pot D' , thus closing the circuit at such point. Current will then pass from main feed-wire 3 through branch wire 2 and wire b^9 to the frame B' of the "down" signal controlling mechanism. From frame B' current will pass by armature-lever c^7 and rod c^8 to mercury-pot D' , and from mercury-pot D' current will pass by wire d^5 to controlling-magnet H^2 , thence by wire d^6 to controlling-magnet H^3 , and thence by wire d^7 and main return feed-wire 5 to source of supply. The controlling-magnets H^2 and H^3 will be thus energized by passage of current therethrough until by mechanism to be hereinafter described the "down" signal controlling mechanism is restored to its normal condition.

At a convenient point upon or within the car is placed the mechanism next to be described whereby the passage of current through the car-signal, preferably an incan-

descent lamp J, is determined and whereby also the passage of current through the restoring-magnets of the "up" and "down" signal controlling mechanism at the floors is determined.

The feed-wire a leads directly to the lamp J, and with the feed-wire a connects a wire a², that is connected by one branch a³ with a circuit-controller K and by a branch a⁴ with a circuit-controller K' and by a branch a⁵ with a circuit-controller K² and by a branch a⁶ with a circuit-controller K³. The construction of each of the circuit-controllers K K', &c., is preferably that illustrated in Figs. 4 and 5 of the drawings—that is to say, within a suitable casing k there is held upon an insulating-block k' a plate-spring k², having attached thereto a soft-iron armature k³, and with the spring k² will be connected the branch wire a³, (or a⁴, a⁵, or a⁶.) Adjacent the armature k³ and fixed to the casing k is a contact-plate k⁴, to which will be connected a leading-out wire k⁵, (or k⁶, k⁷, or k⁸.) that leads to one of the contact-points i of the controlling-switch I. In like manner a wire k⁶ will lead out from the circuit-controller K' to a contact-point i' of the switch I, and in like manner also a wire k⁷ will lead out from the circuit-controller K² to the contact-point i² of this switch. So, also, a wire k⁸ will connect the contact-plate of the circuit-controller K³ with the contact-point i³ of the switch I. The switch I is of familiar form, comprising a series of pivoted arms connected by an insulated handle-bar, the free ends of these arms being so arranged as to connect their pivotal points with either of two different contact-points. From the pivoted ends of the arms of the switch I lead wires m, m', and m², the wire m connecting directly with the return-wire a' and connecting by a branch wire m³ with the frame M of a circuit-controlling mechanism similar to that hereinbefore described, and illustrated in Figs. 2 and 3 of the drawings. The frame M carries the magnets N and N', and this frame is mounted upon an insulating-block N², that supports the mercury-pot N³. At the side of the magnet N extends an arm n, carrying a pivoted armature n', similar in construction and arrangement to the armature b², hereinbefore described. So, also, the upturned end of the frame M, that extends adjacent the magnet N', carries an armature-lever n², similar to the armature-lever c², hereinbefore described, and this armature-lever n² has attached thereto a rod n³, adapted to dip within the mercury-pot N³ and complete the circuit at such point. From the mercury-pot N³ a wire 7 leads to one of the terminals of the signal-lamp J. The central arm of the switch I is connected by the wire m' to the releasing-magnet N, and the wire m², that leads from the switch I, connects to the restoring-magnet N'. The magnets N and N' are connected by the wires p and p', respectively, to the wire p², that leads to the frame M. From the wire a² (that extends

from the leading-in wire a) a branch wire 8 leads to a transfer-button O, from which button a wire 9 connects by branch wires 10 and 11 with the controlling-magnets H² and H⁶ on the car. The controlling-magnet H⁵ is connected by a wire 12 with a contact-point i² of the switch I, and the controlling-magnet H⁶ is connected by a wire 13 with the contact-point i' of the switch I.

From the foregoing description the operation will be seen to be as follows, assuming the parts to be in the position shown by Fig. 1 of the drawings, at which time the car is above the floor at which a "down" signal has been given. It has already been shown that when the "down" push-button E' is operated the rod c² will be caused to drop into the mercury-pot D' of the "down" signal controlling mechanism, thereby closing the circuit at such point and causing the passage of current through the controlling-magnets H² and H⁶. Now when upon the downward movement of the car the circuit-controller K comes opposite the controlling-magnet H³ the soft-iron armature k³ (see Fig. 5) of this circuit-controller K will be attracted by the magnetic force of the controlling-magnet H³ until this armature k³ bears against the contact-plate k⁴, thereby closing the circuit at such point. The result of this closing of the circuit-controller K will be to cause the lighting of the signal-lamp within the car by passage of current in the following manner, viz: From the main feed-wire a current will pass to branch wire a² and branch wire a³ to circuit-controller K, thence by wire k⁵ to contact-point i, thence through switch I by wire m' to releasing-magnet N, thence by wires p and p² to supporting-frame M, thence by wire m² to return feed-wire a'. The current thus passing through magnet N will energize this magnet, thereby attracting its armature-lever n', so as to cause it to release the armature-lever n² and permit the rod n³ to drop into the mercury-pot N³ and complete the circuit at such point. The circuit being thus completed at the mercury-pot, current will pass through the electric lamp J as follows, viz: By leading-in wire a the current will pass from source of supply to lamp J, thence by wire 7 to the mercury-pot N³, by rod n³ to the armature-lever n², to frame M, and thence by wire m² and return feed-wire a' back to source of supply. The lamp J being thus lighted will continue to burn during the down movement of the car for the purpose of signaling the operator until the circuit in which the lamp is placed is broken in the following manner, it being understood that as soon as the circuit-controller K has passed beyond the influence of the controlling-magnet H³ the passage of current through the magnet N is interrupted, viz: When the circuit-controller K' passes to a point opposite the controlling-magnet H², the armature k³ (see Fig. 5) of the circuit-controller K' is attracted against the contact-plate k⁴, and pas-

sage of current is established in the following manner through the magnet N' for the purpose of lifting the rod n^3 out of the mercury-pot N^3 and breaking the lamp-circuit at such point, viz: From leading-in wire a current passes by wire a^2 , branch wire a^4 to circuit-controller K' , thence by wire k^6 to contact-point i^3 of switch I, thence by wire m^2 to magnet N' , thence by wires p' and p^2 to frame M, and thence by wire m^3 and return feed-wire a' to source of supply. The passage of current through the restoring-magnet N' , thus attracting the armature-lever n^2 , lifts the rod n^3 from out the mercury-pot N^3 and breaks the circuit by which current is delivered to the lamp J. As the car continues to pass downward after the signal-lamp therein has been extinguished the controlling-magnet H^5 on the car will come opposite the circuit-controller G' in the hatchway, and the armature K^3 of this circuit-controller G' , being attracted against its contact-plate k^4 , the circuit will be closed at such point. Current will then be caused to pass through the restoring-magnet c^6 as follows, viz: from the rotary transformer or other source of supply by main feed-wire 3 and branch feed-wire g^2 to circuit-controller G' , thence by wire g^3 to restoring-magnet c^6 , thence by wires f^5 and f^6 to wire 4, thence by return feed-wire 5 to rotary transformer or like source of current. The effect of this passage of current through the magnet c^6 is to attract the armature-lever c^7 , thereby lifting the rod c^8 out of the mercury-pot D' and breaking the current through the controlling-magnets H^2 and H^3 . It will be understood, of course, that when the restoring-magnet c^6 is thus energized and the armature-lever c^7 attracted thereby this lever will be caught beneath the free end of the armature-lever b^7 of the magnet b^6 , and it will be plain also that at the several other points of the system in which a restoring-magnet is used like energization will serve to cause the reengagement of its armature-lever by the armature-lever of the adjacent magnet. When the car reaches the bottom of the shaft or the end of its downward travel, the switch I will be shifted from the position shown by full lines to the position shown by dotted lines in Fig. 1 of the drawings. This shifting of the switch I may be effected manually by the operator's moving the knob or handle i^8 to the right or may be effected automatically by the apparatus hereinafter described. It will be understood, however, that while the car is moving in upward direction the switch I will occupy the position shown by dotted lines in the drawings, and when the car reaches the limit of its upward travel the switch will be returned to the position shown by full lines in Fig. 1. If it be assumed that the car is moving in upward direction and an intending passenger wishing to go upward presses the "up" push-button E, the circuit will be closed at such push-button and current will be caused to pass through the releasing-mag-

net b , so as to permit rod c^3 to close the circuit at the mercury-pot D in manner hereinbefore described. The circuit being closed at the mercury-pot D, current will pass to the controlling-magnets H and H' as follows, viz: from main feed-wire 3 by wires 2 and b^5 to frame B, armature-lever c^2 and rod c^3 to mercury-pot D, thence by wire d^2 to controlling-magnet H, thence by wire d^3 to controlling-magnet H' , and thence by wire d^4 to main return feed-wire 5. The controlling-magnets H and H' being thus energized, it will be seen that as the car passes in upward direction from the point below these magnets the circuit-controller K^3 will pass in proximity to the controlling-magnet H' , and at such time this magnet will attract the armature k^3 (see Fig. 5) of this circuit-controller, thereby closing the circuit through such circuit-controller. Current will then pass through the circuit-controller and parts connected therewith as follows, viz: from leading-in wire a by wires a^2 and a^6 to circuit-controller K^3 , thence by wire k^8 to contact-point i^3 , thence by switch I (said switch being in the position shown by dotted lines) and wire m' to releasing-magnet N , thence by wires p and p^2 to frame M, and thence by wire m^3 to the return feed-wire a' . By this means the armature-lever n^2 will be caused to drop, so as to close the circuit at the mercury-pot N^3 . Current will then be caused to pass through the electric lamp J in the manner hereinbefore described, and the lamp J will continue to burn until in the upward movement of the car the circuit-controller K^2 comes opposite the controlling-magnet H, which magnet by attracting the armature k^3 of the circuit-controller will close the local circuit at such point. Current will then be caused to pass through the circuit-controller K^2 as follows, viz: from leading-in wire a to branch wire a^2 and branch a^5 to circuit-controller K^2 , thence by wire k^7 to contact-point i^2 of switch I, thence by switch I and wire m^2 to restoring-magnet N' , thence by wires p' and p^2 to frame M, and thence by wire m^3 to leading-out wire a' . The energization of the restoring-magnet N' will return the armature-lever n^2 of this magnet to locked position, (shown in Fig. 1 of the drawings,) thereby breaking the circuit at the mercury-pot N^3 and extinguishing the lamp. During the further upward movement of the car the controlling-magnet H^6 thereon will pass opposite the circuit-controller G in the hatchway, thereby closing the circuit through such circuit-controller so as to cause the passage of current through the restoring-magnet c , and thus return the armature-lever c^2 to the locked position (seen in Fig. 1) and break the circuit through the mercury-pot D. Instead of operating the switch I on the car manually, as hereinbefore described, this switch may be operated automatically by the mechanism illustrated in Figs. 10, 11, and 12 of the drawings. To this end the contact-points of the switch will consist of mercury-

pots r , r' , r^2 , r^3 , r^4 , and r^5 , into which will dip the rods 15, carried, respectively, by the switch-arms s , s' , s^2 , s^3 , s^4 , and s^5 . These switch-arms are fixed upon a rock-shaft S, insulating-
5 sleeve s^6 being interposed between the hubs of the switch-arms and the shaft. Against the hubs of the switch-arms s , s' , &c., bear the corresponding spring-plates s^7 , s^8 , and s^9 , that are connected, respectively, to the wires m , m' , and m^2 , hereinbefore described, and it will be understood that the mercury-pots r , r' , &c., will correspond with the several contact-points of the switch shown in Fig. 1 of the drawings, these mercury-pots being connected
10 with the corresponding wires that lead to such contact-points. The shaft S is mounted in suitable standards 17 and 18, supported upon an insulated base 19, that is suitably supported at a convenient point of the car.
15 The outer projecting end of the rock-shaft S has fixed thereto a soft-iron armature S', that will be attracted by one or the other of the controlling-magnets T and T', that are shown as located, respectively, at the top and bottom of the elevator-hatchway. The controlling-magnets T and T' are the same in construction as the controlling-magnet H, (illustrated in Figs. 6 and 7 of the drawings,) and these magnets are connected by branch wires
20 t and t' with the return feed-wire 5 of the main circuit and by branch wires t^2 and t^3 with their respective switches T' and T², these switches being connected, respectively, with the main leading-in feed-wire 3 by the branch
25 wires t^4 and t^5 . The controlling-magnets T and T' will be so located in the elevator-hatchway that as the car reaches the limit of its upward travel the armature-lever S' will be attracted by the controlling-magnet T and
30 will be shifted from the position shown in Fig. 11, so as to break the contact at the mercury-pots r , r' , and r^2 and establish contact at the mercury-pots r^3 , r^4 , and r^5 . So, also, when the car reaches the limit of its
35 downward movement the armature-lever S' will come adjacent to the controlling-magnet T' and will be returned to the position seen in Fig. 11 of the drawings, thereby shifting the switch and establishing contact at the
40 mercury-pots r , r' , and r^2 .

As it sometimes happens, particularly in very tall buildings, that during certain hours of the day an elevator will run only to a certain floor below the upper floor of the building, while at other hours it will make the complete travel of the hatchway, it may be desired to provide a controlling-magnet T at other floors of the building below the top. It is for this reason that the switch T' is employed, since when the switch is turned from the closed position (seen in full lines) to the open position (shown by dotted lines in Fig. 10) the controlling-magnet T at any floor can be thrown out of action. For example, if
45 during certain hours of the day the car is running, say, to the fourth floor only the controlling-magnet T will be employed at such

floor to automatically reverse the switch within the car; but if at other hours of the day the car makes the full run of the hatchway 70 the controlling-magnet at the fourth floor will be switched out of action.

In some systems of electric signaling apparatus for elevator-cars it is desirable not only that the operator of the car shall receive a 75 signal, but also that lanterns or other signals located at each floor shall be brought into operation, so as to indicate to an intending passenger the approach of the next elevator-car coming in the desired direction. When floor-lanterns or like signals are desired, the system of wiring illustrated in Fig. 13 of the drawings will be used. The "up" signal and "down" signal controlling mechanism illustrated in Fig. 13 is the same as that hereinbefore described, and with the exceptions hereinafter noted the wiring is similar. So, also, the controlling-magnets H, H', &c., and the circuit-controllers G and G' are constructed and operated as hereinbefore described. Adjacent 80 the hatchway of the elevator are located two signals W and W', commonly termed "floor-lanterns," the signal W serving to indicate to the intending passenger the approach of the elevator-car in upward direction, while the 85 lantern W' serves to indicate the approach of a car moving in downward direction. The "up" lantern W is connected by a wire w with the controlling-magnet H, from which a wire d^8 leads to the controlling-magnet H', 90 this controlling-magnet H' being connected by a wire d^9 with a circuit-closer V, that is connected by a wire v with the main return feed-wire 5. In like manner one terminal of the "down" lantern is connected by a wire w' with the controlling-magnet H', from which magnet a wire w^2 leads to a circuit-closer V', 95 that is connected by a wire v' to the main return feed-wire 5. The construction of the circuit-closers V and V' is identical and is 100 illustrated in Figs. 8 and 9 of the drawings. Each of these circuit-closers V and V' comprises an electromagnet v^3 , that is mounted upon an insulating-block 40, preferably carried by a casing or like support 41, that will 105 be mounted at a suitable point within the elevator-shaft. The armature v^3 is pivoted, as at 41, to the bracket 42, this armature being shown as provided with an arm 43, adapted to contact with a set-screw 44, that limits its 110 rearward movement. A soft-iron head v^4 , attached to the armature v^3 , serves to hold the contact-point 45 of the armature normally away from a contact-point 46 on the soft-iron head 47 of the magnet v^3 , and the head 47 is 115 connected by a wire 48 with the coil of the magnet. The opposite end of the magnet-coil v^3 in the circuit-closer V is connected to the wire v , and the metal bracket 42 of this circuit-closer is connected to the wire d^8 . In 120 the case of the circuit-closer V' the wire that leads from the magnet v^3 is connected to the wire w^2 , while the wire that leads from the bracket 42 is connected to the wire v' , that

leads to the return feed-wire 5. From the "up" signal-lantern *w* a wire 50 leads to the mercury-pot *D* of the "up" signal controlling mechanism, and from the "down" signal-lantern *W'* a wire 51 leads to the controlling-magnet *H*², that is connected by a wire *d*⁵ (as in the construction before described) with the mercury-pot *D'* of the "down" signal controlling mechanism. In this form of my invention the wires *f* and *f*² of the "up" signal controlling mechanism are connected by wires *f*⁹ with the frame *B*, and in like manner the wires *f*⁴ and *f*⁵ between the magnets of the "down" signal controlling mechanism are connected by a wire *f*¹⁰ to the frame *B'*. The frames *B* and *B'* are connected by the wires 31 and 30 with the main feed-wire 3. It will be understood that the circuit-closers *V* and *V'* will be arranged in the elevator-shaft at considerable distance—say the distance of a floor or two—from the floor at which are located the signal-lanterns *W* and *W'* controlled by these circuit-closers, so that an intending passenger will have ample notice of the approach of the elevator-car.

From the foregoing description it will be seen that when a passenger desiring "up" service depresses the "up" push-button *E* and closes the circuit at such point current will pass from the main feed-wire 3 by wires 30 and 31 to the frame *B*, thence by wires *f*⁹ and *f* to the releasing-magnet *b*, thence by wire *e*² to the push-button *E*, thence by wire 54 to the return feed-wire 5. The effect of this passage of current will be to cause the closing of the circuit at the mercury-pot *D* in manner hereinbefore described. As the elevator-car in its upward travel causes the controlling-magnet *H*⁶ to pass adjacent the circuit-closer *V*, this magnet *H*⁶ will attract the armature *v*³ of the circuit-closer *V*, causing the contact-points 45 and 46 to come together. Current will then pass through the "up" signal-lantern *W* and through the "up" circuit-closer *V* as follows, viz: from main feed-wire 3 by wires 30 and 31 to the frame *B*, thence by armature-lever *c*² and its rod to mercury-pot *D*, thence by wire 50 to one terminal of the "up" signal-lantern *W*, thence by wire *w* to controlling-magnet *H*, thence by wire *d*³ to controlling-magnet *H*¹, thence by wire *d*¹⁰ to circuit-closer *V*, thence through the armature and through the magnet of the circuit-closer to wire *v*, and by this wire and the return feed-wire 5 back to source of current. The "up" signal-lantern *W* will thus be caused to burn and indicate to the intending passenger that a car is approaching in upward direction. As soon, however, as the car in its upward travel brings the controlling-magnet *H*⁶ opposite the circuit-controller *G* current will be caused to pass through the restoring-magnet *c* in manner hereinbefore described, thereby energizing this magnet and causing the breakage of circuit at the mercury-pot *D*. The "up" signal-lantern *W* will then cease to burn. In like manner it

will be seen that when an intending passenger desiring to descend depresses the "down" push-button *E'* the circuit will be closed at the mercury-pot *D'*, causing passage of current from main feed-wire 3 by wires 30 and 31 to frame *B'*, by wires *f*¹⁰ and *f*⁴ to magnet *b*⁶, by wire *e*³ to push-button *E'*, by wires 58 and 54 to return feed-wire 5. Current will then pass through the "down" signal-lantern *W'* as follows, viz: from main feed-wire 3 by wires 30 and 31 to frame *B'*, by armature-lever *c*⁷ and its rod to mercury-pot *D'*, by wire *d*⁵ to controlling-magnet *H*², by wire 51 to one terminal of "down" signal-lantern *W'*, by wire *w'* to controlling-magnet *H*³, by wire *v*³ to circuit-closer *V'*, and from this circuit-closer by wire *v'* to main return feed-wire 5. When the car in its downward travel causes this controlling-magnet *H*⁵ to pass opposite the armature of the circuit-closer *V'*, the circuit at such circuit-closer will be completed and current will then pass through the "down" signal-lantern *W'*, causing this lantern to burn and to indicate to the intending passenger the down approach of the car. As soon, however, as the car in its downward movement brings its controlling-magnet *H*⁵ opposite the circuit closer *G'* the circuit at such circuit-closer will be completed and current will be caused to pass in manner hereinbefore described through the restoring-magnet *c*⁶ of the "down" signal controlling mechanism, thereby causing the circuit to be broken at the mercury-pot *D'*. When the circuit is thus broken at the mercury-pot *D'*, the "down" signal floor lantern *W'* will cease to burn.

It will be understood that when my invention is employed upon elevators that are arranged in a "bank" or series the "up" and "down" signal controlling mechanism at the several floors of the building will actuate the signal within all the cars of the series. As it frequently happens that a car first to approach a landing at which a signal has been given is too crowded to receive an intending passenger, it is desirable that provision be made so that the signal given by the passenger shall stand in the next approaching car. For this reason each car is provided with a transfer-button *O*, that consists of a simple normally closed switch or push-button interposed in the circuit by which current is delivered to the controlling-magnets *H*⁵ and *H*⁶ on the car. Now as these controlling-magnets serve to restore the "up" and "down" signaling mechanism at each floor to normal condition it is manifest that if the push-button *O* be opened by the operator as the car passes the floor at which the signal has been given the controlling-magnets *H*⁵ and *H*⁶ will be inactive, and therefore will not affect the circuit-controllers of the "up" and "down" signal controlling mechanism, and consequently said signal-controlling mechanism will still continue to operate the signals within the other cars of the series.

While I have described what I regard as the preferred embodiment of my invention, it will be readily understood that many changes in the construction, location, and arrangement of parts may be made by persons skilled in the art without departing from the spirit of the invention.

Having thus described my invention, what I claim as new, and desire to secure by Letters

10 Patent, is—

1. An electrical signaling system for elevators consisting of two main parts, one of said parts comprising a signal, an operating-circuit therefor and controlling means for said circuit, and the other of said parts comprising two separate electrical devices and an energizing-circuit therefor, one of said main parts being so located on the car and the other so located in the elevator-shaft that said controlling means will successively pass through the magnetic fields of said separate electrical devices and be automatically actuated by one of said electrical devices to first actuate said signal and by the second electrical device to automatically restore said signal to normal condition.

2. An electric signaling apparatus for elevators, comprising a signal on the car, an electric circuit for said signal, a circuit-controller on the car and whereby the passage of current through said circuit is determined, a controlling-magnet in the elevator-shaft and located adjacent the path of travel of said circuit-controller so that the latter passes through the magnetic field of said controlling-magnet and is actuated thereby, an electric circuit wherein said magnet is placed, a push-button or like circuit-controlling mechanism within said last-named circuit and automatically-operating means for restoring the car-signal to normal condition.

3. An electric signaling apparatus for elevators comprising a signal on the car, an electric circuit wherein said signal is placed, a circuit-controller located upon the car and serving to operate said signal, a second circuit-controller located upon the car and serving to restore said signal to normal condition, a controlling-magnet located adjacent the path of and serving to actuate said first-mentioned circuit-controller on the car, and a second controlling-magnet located adjacent the path of and serving to actuate said second circuit-controller on the car and suitable means for causing the passage of current through said controlling-magnets.

4. An electric signaling apparatus for elevators comprising a signal upon the elevator-car, an electric circuit for operating said signal, two controllers for said circuit, one of said circuit-controllers serving to bring said signal into action and the other of said circuit-controllers serving to restore said signal to normal condition, magnetic means located within the elevator-shaft for successively actuating said circuit-controllers, an electric circuit for energizing said magnetic means

and a push-button or similar controller for said last-mentioned circuit.

5. An electric signaling apparatus for elevators, comprising a signal upon the elevator-car, an electric circuit wherein said signal is placed, two circuit-controllers in said car-circuit, one of said circuit-controllers serving to bring said signal into action and the other of said circuit-controllers serving to restore said signal to normal condition, two controlling-magnets located within the elevator-shaft, one of said controlling-magnets being arranged adjacent the path of said first-mentioned circuit-controller on the car and the other of said magnets being arranged adjacent the path of said second circuit-controller on the car, an electric circuit wherein said magnets are interposed and suitable circuit-controlling mechanism for causing the passage of current through said circuit-controlling magnets.

6. An electric signaling apparatus for elevators comprising a signal upon the car, an electric circuit wherein said signal is interposed, a circuit-controller for said circuit, a controlling-magnet located in the elevator-shaft adjacent the path of travel of said circuit-controller, an electric circuit wherein said controlling-magnet is placed, a push-button or like circuit-controlling mechanism for determining the passage of current through said controlling-magnet, a controlling-magnet located upon the car, means for causing the passage of current through said last-mentioned controlling-magnet, a circuit-controller located in the elevator-shaft adjacent the path of travel of the controlling-magnet on the car, an electric circuit wherein said last-mentioned circuit-controller is placed and suitable means operated by said last-mentioned circuit-controller to break the circuit through said controlling-magnet in the shaft.

7. An electric signaling apparatus for elevators, comprising a signal located on the car, an electric circuit wherein said signal is placed, a circuit-controller on the car for effecting the passage of current through said signal-circuit, a controlling-magnet located in the elevator-shaft adjacent the path of said circuit-controller, an electric circuit wherein said magnet is placed, a releasing-magnet whereby the circuit through said controlling-magnet is completed, a push-button or like mechanism whereby the passage of current through said releasing-magnet is effected, a second circuit-controller located upon the car and serving to restore the car-signal to normal condition, a second controlling-magnet located within the elevator-shaft and serving to actuate said second circuit-controller, a controlling-magnet located upon the car, means for causing the passage of current through said last-mentioned controlling-magnet, a circuit-controller located in the elevator-shaft adjacent the path of the controlling-magnet on the car, and a restoring-magnet in circuit

with said last-named circuit-controller and serving to effect the breakage of current through said controlling-magnets in the shaft.

8. An electric signaling apparatus for elevators, comprising a signal on the car, an electric circuit wherein said signal is placed, a releasing-magnet for closing at one point said electric circuit, a circuit-controller for completing the closing of said electric circuit, a restoring-magnet for effecting the breakage of said electric circuit to restore the signal to normal condition, a second circuit-controller for closing the circuit to cause the passage of current through said restoring-magnet, two controlling-magnets located in the elevator-shaft adjacent the path of travel of said circuit-controllers on the car, an electric circuit wherein said controlling-magnets are placed and push-button or like mechanism for determining the passage of current through said controlling-magnets.

9. An electric signaling apparatus for elevators comprising the combination with a signal on the car, of an electric circuit for operating said signal, "up" and "down" controllers for said signal-circuit carried by the car, "up" and "down" signal controlling magnets located in the elevator-shaft, energizing-circuits for said magnets and "up" and "down" push-buttons or similar controllers for said energizing-circuits, the parts being so arranged that the signal-circuit controllers on the car will pass through the magnetic fields of the controlling-magnets in the shaft.

10. An electric signaling apparatus for elevators, comprising the combination with a signal on the car, of an electric circuit wherein said signal is placed, two circuit-controllers for "up" signaling purposes and two circuit-controllers for "down" signaling purposes carried by the car, switch mechanism for throwing either set of said controllers into or out of circuit, a pair of "up" signal controlling magnets and a pair of "down" signal controlling magnets located in the elevator-shaft, an "up" signal controlling mechanism and a "down" signal controlling mechanism in circuit with their respective controlling-magnets and "up" and "down" push-buttons for determining the passage of current respectively through the "up" and "down" signal controlling mechanism.

11. In electric signaling apparatus for elevators, the combination with a signal on the car, of an electric circuit wherein said signal is placed, two circuit-controllers for "up" signaling purposes and two circuit-controllers for "down" signaling purposes carried by the car, switch mechanism for throwing either set of said controllers into or out of circuit, means for automatically shifting said switch mechanism at the end of the car travel, a pair of "up" signal controlling magnets and a pair of "down" signal controlling magnets located in the elevator-shaft, an "up" signal controlling mechanism and a "down"

signal controlling mechanism in circuit with their respective controlling-magnets and "up" and "down" push-buttons for determining the passage of current respectively through the "up" and "down" signal controlling mechanism.

12. An electric signaling apparatus for elevators, comprising the combination with the signal on the car, of an electric circuit wherein said signal is placed, two circuit-controllers for "up" signaling purposes and two circuit-controllers for "down" signaling purposes carried by the car, switch mechanism for throwing either of said controllers into or out of circuit, means for automatically shifting said switch mechanism comprising a shifting-armature connected with said switch mechanism and a controlling-magnet adapted to attract said shifting-armature and a circuit wherein said controlling-magnet is placed and suitable means exterior to the car for operating said controllers.

13. An electric signaling apparatus for elevators, comprising a signal on the car, of an electric circuit wherein said signal is placed, two circuit-controllers for "up" signaling purposes and two circuit-controllers for "down" signaling purposes carried by the car, switch mechanism for throwing either set of circuit-controllers into or out of circuit comprising a rock-shaft having a series of arms at opposite sides thereof and having a shifting-armature at its end and two controlling-magnets located at the opposite points of travel of the armature and arranged to attract said armature in opposite directions and suitable means exterior to the car for operating said controllers.

14. An electric signaling apparatus for elevators, comprising a signal located on the car, an electric circuit wherein said signal is placed, a circuit-controller carried by the car and arranged to effect the passage of current through said signal, a second circuit-controller carried by the car and arranged to restore said signal to its normal condition, suitable means within the elevator-shaft for actuating said circuit-controllers at proper times, and a transfer-button whereby the passage of current through said second circuit-controller may be prevented in order to prevent the restoration of the signal to normal condition by said second controller.

15. An electric signaling apparatus for elevators, comprising a signal located on the car, an electric circuit wherein said signal is placed, a releasing-magnet N and a restoring-magnet N' provided with interlocking armatures, a suitable contact for completing the circuit by releasing the armature of the restoring-magnet, a switch having its fixed terminals connected by suitable wires with said releasing and restoring magnets and with the part that engages said mercury-pot, a pair of "up" signaling circuit-controllers and a pair of "down" signaling circuit-controllers located upon the car, said circuit-controllers

being suitably connected with the contact-points of said switch, controlling-magnets located within the elevator-shaft and adapted to actuate said circuit-controllers carried by the car, and suitable "up" signaling and "down" signaling devices for determining the passage of current through said controlling-magnets within the elevator-shaft.

16. An electric signaling apparatus for elevators, comprising the combination with a signal on the car, suitable circuit-controllers and adjunctive devices carried by the car whereby the passage of current through said signal is determined, controlling-magnets within the elevator-shaft for actuating said circuit-controllers carried by the car, a circuit-controller within the shaft and suitable adjunctive devices whereby the passage of current through said controlling-magnets is determined, and a controlling-magnet mounted upon the car and adapted to actuate said circuit-controller within the shaft.

17. An electric signaling apparatus for ele-

vators comprising signals located at the separate floors of the building, suitable energizing-circuits for said signals, two circuit-controllers for each of said signal-circuits, means for manually operating one of said circuit-controllers and means carried directly on the car for automatically operating the other of said circuit-controllers.

18. An electric signaling apparatus for elevators, comprising floor signal-lanterns W and W', an "up" signaling mechanism in circuit with the signal-lantern W and a "down" signaling mechanism in circuit with the lantern W', a circuit-controller V in circuit with the "up" signal-lantern W, a circuit-controller V' in circuit with the "down" signal-lantern W', controlling-magnets on the car and means for causing passage of current through said controlling-magnets.
